UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

1,136,737.

Specification of Letters Patent. Patented Apr. 20, 1915.

Application filed July 10, 1914. Serial No. 850,208.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Switch, of which the following is a specification.

My invention relates to electric switches, 10 particularly to flush switches of the push button type and the object of my invention is to provide an improved construction therefor having the advantages hereinafter mentioned and shown in the accompanying 15 drawings in which—

Figure 1 is a broken side elevation of a push button switch in which my invention is embodied in one form; Fig. 2 is an end elevation thereof; Fig. 3 is a side elevation of 20 the base alone, showing the switch mechanism thereon and partially broken away; Fig. 4 is a perspective of one of the combined wire and switch terminals; and Fig. 5 is a perspective of certain details of the 25 switch, detached.

The present switch mechanism is mounted in an insulating casing 10 comprising a shallow cup-shaped base A and an inverted cup-shaped cap B of substantially the same 30 construction, and fitting thereon in assembled position so as to completely inclose the switch mechanism. The latter is carried by a frame 11 mounted on the base A and comprises the usual switch blades 12, rocker 13 and push 35 buttons 14 attached to the latter. The combined wire and switch terminals 15 are mounted at the corners of the base A and project well above the low sides of the latter, thus affording ready access to the 40 terminal wings 16 so that the latter may be adjusted with relation to the blades 12 after the parts have been assembled upon the base. Adjustments of this character are usually 45 necessary by reason of the fact that irregularities in the porcelain commonly occur during the baking of the latter, with the consequence that variations occur in the positions of the terminals with relation to the switch mechanism carried by the standard 11. The 50 adjustment of these terminals with relation to the switch blades is much facilitated by the present construction, since the wings 16 are readily accessible and may be easily bent into alinement with the switch blades 12 by

the simple manipulation thereof, by means 55 of a pair of pincers.

The cap B is apertured at 17, at its four corners, in register with the binding screws 18 so that in adjusted position the heads of the latter are exposed to receive beneath the 60 same the ends of the leading-in wires. A carrying yoke 19 is set into a longitudinal recess in the upper face of the cap and is secured in position by screws 20 passing upward through the base A and cap B and 65 taking into threaded holes in the yoke. Both portions of the insulating casing are thus secured together, as well as to the yoke by the screws 20, one at each end of the fitting.

The switch mechanism is on the whole of 70 usual construction. The detent slide 21 however is normally pressed down into position to engage the cross bar 22 of the switch blades by a leaf spring 23. The latter is secured to one upright 11 at 24 and stretches 75 across to the other standard adjacent which the detent slide 21 mounted and above which it slightly projects. Lugs 25 on the rocker engage beneath shoulders 26 formed in the upper portion of the detent slide and raise 80 the latter against the pressure of the spring as the rocker nears the completion of its downward stroke in either direction.

The spindle 27 upon which the switch 85 mechanism is mounted may be freely passed through the opposite sides of the standard 11 and is retained in position by the juxtaposed sides of the cap which prevent the lateral escape of the spindle from its bearings.

The two-part construction of the insulating casing is of special value in facilitating the assembly and adjustment of the switch mechanism and terminals upon the base while the assembly of the same with the yoke by means of securing screws, one at 90 each end of the fitting, makes a very simple and rigid construction readily manufactured and put together. The switch parts are completely inclosed and the wire terminals well insulated from each other and protected by 95 surrounding porcelain, while at the same time they are conveniently exposed for 100 wiring.

I claim as my invention:—

1. A device of the character described, 105 comprising a two-piece insulating body, a carrying yoke therefor and securing bolts passing through both pieces of the insu-

lating body and engaging said yoke to hold the several parts in assembled condition.

2. A device of the character described, having a two-piece insulating body comprising a shallow cup-shaped base, wire terminals and switch mechanism mounted thereon, and an independent cap of corresponding contour fitting upon said base in assembled position and inclosing said switch mechanism, and means for securing said cap and base together.

3. A device of the character described, having a two-piece insulating body comprising a shallow cup-shaped base, wire terminals and switch mechanism mounted thereon, and an independent cap of corresponding contour fitting upon said base in assembled position and inclosing said switch mechanism, together with a carrying yoke 20 adjustable on said cap and means for securing said body parts and yoke together.

4. A device of the character described, having a two-piece insulating body comprising a shallow cup-shaped base, wire terminals and switch mechanism mounted thereon, and an independent cap of corresponding contour fitting upon said base in assembled position and inclosing said switch mechanism, said cap being apertured to expose the wire terminals in the assembled position of the parts.

5. A device of the character described, having a two-piece insulating body comprising a shallow cup-shaped base, wire terminals mounted thereon and upstanding above the walls of said base and an independent cap of corresponding contour resting upon said base and having apertures in its top to expose said wire terminals.

40 6. A device of the character described,

having a two-piece insulating body of general rectangular shape and comprising a shallow cup-shaped base, wire terminals mounted in the corners of said base and upstanding above the walls thereof, and an independent cap of corresponding contour resting upon said base and having apertures in its top to expose said wire terminals.

7. A device of the character described, having a switch mechanism comprising a pair of uprights, a sliding detent mounted adjacent one of said uprights, together with a plate spring carried by the other of said uprights and engaging said detent, for the purpose described.

8. A device of the character described, having a switch mechanism comprising a pair of uprights, a sliding detent mounted adjacent one of said uprights and extending above the same, together with a plate 60 spring carried by the other of said uprights resting upon the top of said detent, for the purpose described.

9. A device of the character described, having a switch mechanism, comprising an 65 upright, a sliding detent mounted adjacent the same and having its upper end shouldered, a switch spindle, a rocker pivoted above and eccentrically thereto adjacent the detent and lugs struck therefrom and engaging the shoulders of the detent to lift the latter, substantially as described.

In testimony whereof I have signed my name to this specification, in the presence of two subscribing witnesses.

GEORGE B. THOMAS.
